ALBERT H. TAYLOR AND LEO C. YOUNG, OF WASHINGTON, DISTRICT OF COLUMBIA.

RECEIVING SYSTEM FOR HIGH-FREQUENCY ELECTRICAL OSCILLATIONS.

Application filed January 19, 1924. Serial No. 637,255.

While our invention relates generally to systems for receiving high frequency electrical oscillations, has for a particular object the employment of a plurality of tuned receivers 5 with a single collector of the high frequency oscillations.

A further object is the reception of a plurality of communications at different frequencies, and providing means to prevent 10 the tuning operations of the receivers from interfering one with the other through adjustment of the tuning elements.

Our invention is of particular value for instance in receiving radio signals in locations where there are limitations restricting the number of antennae which can be erected though it may be desired to receive a large 15 number of signals, which condition may be encountered on board ships, in hotels or in 20 apartment houses. With our system a single antenna can be erected on the roof of a building, numerous branch circuits from this collecting antenna lead to the various rooms of the building, and receiving systems connected to these branch circuits can be operated 25 at the will of the occupants of one room without interference to the operation of similar systems located in the other rooms of the building.

30 Our invention will be best understood by reference to the figure of the drawing which illustrates the invention used in connection with the reception of radio signals.

A is an antenna collector of conventional 35 form grounded at G. B₁ is a branch circuit in series with the antenna A containing a high resistance R₁, preferably of the order of 50,000 ohms. In series with the resistance R₁ is the double-pole double-throw switch 40 S₁. To one pair of terminals of this switch there is connected a high resistance R_{1'}, preferably of the order of one half a megohm, and to the other pair of terminals there is connected a tunable circuit containing 45 inductance L₁ and variable capacity C₁. In shunt to the switch S₁ we connect a receiver, one connection being made through a variable contactor V₁, the contact being variable over the extent of the resistance R₁. 50 The receiver illustrated includes a radio frequency amplifier in two steps containing the three-electrode vacuum tubes VT₁ and VT_{1'} interlinked through the radio frequency transformer RF. The output of the 55 radio frequency amplifier is delivered to a vacuum tube rectifier VT_{1''} through a re-

sistance R₅ and the tuned couplings comprising inductance L₅ and variable condenser C₅ in the plate circuit of the last stage of radio frequency amplification and inductance L₆ and variable condenser C₆ in the grid circuit of the detecting vacuum tube. Inductance L₇ in the plate circuit of the detecting vacuum tube coupled to the inductance L₈ in the grid circuit provides for additional amplification of the signal through re-generation, or for producing oscillations for reception of sustained wave signals by the autodyne method of obtaining beats. The resistance R₈ and shunted capacity C₇ 70 form the well known grid-leak stopping-condenser combination in circuit arrangements of this kind. Battery B₅ provides for heating currents for the filaments of the vacuum tubes, the amount of heating current 75 for vacuum tube VT₁ and VT_{1'} being controlled through rheostat R₇ and for vacuum tube VT_{1''} through rheostat R₈. Battery B₈ supplies the plate circuit energy for these vacuum tubes. T is a telephone or other 80 responsive device shunted by the radio frequency by-pass condenser C₈.

B₂ is a second branch circuit in series with the collecting antenna A, but in parallel with branch circuit B₁, containing resistance R₂, switch S₂, resistance R_{2'}, tunable circuit containing inductance L₂ and variable capacity C₂, all substantially of the same arrangement and values as described in connection with branch circuit B₁. A receiver 90 is also connected to this branch circuit in shunt with the switch S₂, and through a variable contactor V₂ to resistance R_{2'}, the receiver having a radio frequency amplifier of which the vacuum tube VT₂ is the first 95 stage, all substantially as described in connection with branch circuit B₁.

Any number of branch circuits as B₃ and B₄ indicated by arrows may be added to the system to include elements substantially as heretofore described.

The operation of the system is as follows:

If it is desired to receive a signal at a given frequency on anyone of the branch circuits such as B₁, the switch S₁ is thrown to the right to include the resistance R_{1'} in series with the resistance R₁. The variable contactor V₁ is preferably moved to the top of the resistance R₁ to include all of this resistance between the grid and filaments leads to the vacuum tube VT₁. This adjustment we term the "hunting position". The

condensers C_5 and C_6 are then adjusted until the desired signal is best heard, then leaving these condensers at the adjusted setting the switch S_1 is thrown to the left to include the tunable circuit containing inductance L_1 and variable capacity C_1 in series with the resistance R_1 , and the variable condenser C_1 adjusted until maximum intensity of signal is obtained. Improved selectivity 10 may be obtained by moving the variable contactor V_1 to the lower part of the resistance R_1 , leaving the vacuum tube VT_1 in shunt with the tunable circuit only.

Any number of the receivers connected to 15 the branch circuits may be put into operation in the same manner, and we have found that with the system substantially as illustrated the carrying out of the adjustments for the independent receivers does not interfere with 20 the adjustment of other receivers which may be in operation.

We have found that delivering the output 25 of the radio frequency amplifier to its coupled detector circuit through resistance R_5 , of approximately 5000 ohms, improves the selectivity of the system.

The non-interfering properties of the system can undoubtedly be ascribed to the aperiodic condition in which the antenna is 30 always maintained by the comparatively high resistances R_1 , R_2 etc. in the branch circuits. These resistances do not materially decrease the receiving efficiency of the system, for even though their resistances are 35 high yet the impedances of the tunable circuits in series therewith are materially greater for signals of the desired frequency. At the same time these resistances keep signals

of undesired frequencies out of the branch circuits to a considerable extent, and those 40 parts of the signal which do enter encounter low impedances in the tunable circuits to which the undesired frequencies are not in resonance, and therefore transfer low values of potential to the shunted receivers. 45

Having described our invention we claim:

1. In a system for receiving high frequency oscillations the combination of a collector for said oscillations, a plurality of branch circuits connected in series with said 50 collector and in parallel with each other, each branch circuit containing a high resistance and a parallel tunable circuit in series with said resistance, and a receiver connected to each of said branch circuits in 55 a position in shunt with said parallel tunable circuits and any selected portion of said high resistances.

2. In a system for receiving high frequency oscillations the combination of a collector for said oscillations, a plurality of branch circuits connected in series with said 60 collector and in parallel with each other, each branch containing a high resistance and having a parallel tunable circuit and a resistance substantially higher than said first resistance together with means for alternately connecting it in series with said first resistance, and receivers operated by the difference of potentials created by the collected oscillations at the terminals of the 65 connections for said parallel tunable circuit and second high resistance. 70
